Atty.

UNITED STATES PATENT OFFICE.

FRANK PINCH, OF SIDNEY, NEW YORK.

ROD-PACKING.

SPECIFICATION forming part of Letters Patent No. 374,905, dated December 13, 1887.

Application filed April 19, 1887. Serial No. 235,372. (No model.)

To all whom it may concern:

Be it known that I, FRANK PINCH, of Sidney, in the county of Delaware and State of New York, have invented certain new and 5 useful Improvements in Rod-Packings, of which the following is a specification, reference being had to the accompanying drawings, and to the letters of reference marked thereon.

The object of the invention is to make a perfect steam or water tight joint which shall be self-adjustable, to compensate for the settling of the rod consequent upon the wear of the bush-ring of the steam-chest stuffing-box; and the invention relates more particularly to a 15 casing adapted for use with adjustable packing for valve and other rods.

In the accompanying drawings, Figure 1 is a longitudinal section. Fig. 2 is a front view, and Fig. 3 a rear view, of the invention.

20 Similar letters of reference indicate similar parts in the respective figures.

A is a casing, the rear part of which is grooved or channeled for the reception of the elastic packing a, which bears against the 25 stuffing-box B of the valve-chest. The bush-ring of the stuffing-box is shown by C. The valve-rod D, when in its normal position and before wear of the bush-ring C, is concentric or in line with the rear portion, b, of the case 30 A, as shown in the drawings.

E shows any approved ring-packing which will adjust itself to the diameter of the rod by the action of the steam. I do not limit myself to the construction of the ring-packing, as it 35 may be of any suitable well-known character. The ring-packing is held forward within the casing A by means of the spring F, which surrounds the rod.

It will be noticed, by reference to Fig. 3, 40 that the lower front part, e, of the casing A is eccentric with the rear portion, d, or with the

longitudinal center of the rod when in its original or normal position. The said lower and forward part of the casing is provided with a space or chamber, e, of a length at least 45 equal to the length of the ring-packing. The bore or hole in the front of the casing A is preferably oblong, as shown; but this is immaterial, as the opening is of such size as not to be in contact with the rod. The inner face, 50 f, of the casing A and the corresponding face of the ring g in front of the ring-packing are made steam-tight by grinding.

It will be seen that by the reciprocating movement of the rod the bush-ring in the 55 stuffing-box of the steam-chest will be worn, and that unless provision is made whereby the rod may settle or fall the packing will come in contact with the casing and a steam-joint cannot be made. By the use of the chamber 60 or space e the ring-packing can fall or settle, thus accommodating itself to the fall of the rod consequent upon the wear of the bush-ring.

This invention is therefore important in allowing the packing to be self-adjusting as the 65 rod settles.

Having described my invention, I claim—
In a rod-packing device, the combination of the stuffing-box B, the casing A, and an adjustable ring-packing within the casing 70 adapted to surround the rod, the casing having the lower front chamber, e, eccentric with the rear portion, b, and of a length equal to that of the ring-packing, substantially as set forth.

75 In testimony whereof I have hereunto set my hand and seal.

FRANK PINCH. [L. S.]
